UNITED STATES PATENT OFFICE

144,040

DESIGN FOR A BABY CARRIER OR SIMILAR ARTICLE

Chris A. De Pirro, Chicago, Ill.

Application June 2, 1945, Serial No. 119,868

Term of patent 14 years

(Cl. D58—4)

To all whom it may concern:

Be it known that I, Chris A. De Pirro, a citizen of the United States, and residing in the city of Chicago, in the county of Cook and State of Illinois, have invented a new, original, and ornamental Design for a Baby Carrier or Similar Article, of which the following is the specification, reference being had to the accompanying drawing, forming a part thereof.

On the drawing:

Fig. 1 is a front elevational view of a baby carrier, or similar article, embodying my new design with the handle broken away for convenience of illustration;

Fig. 2 is an end elevation thereof;

Fig. 3 is a top plan view thereof with the handle omitted, and;

Fig. 4 is a perspective view of the entire baby carrier, or similar article.

I claim:

The ornamental design for a baby carrier or similar article, substantially as shown.

CHRIS A. DE PIRRO.
